UNITED STATES PATENT OFFICE.

RANSFORD WILCOX AND SAMUEL L. PHILLIPS, OF MILWAUKEE, WISCONSIN.

MACHINE FOR REDUCING WHEAT AND ANALOGOUS GRAIN.

SPECIFICATION forming part of Letters Patent No. 359,587, dated March 15, 1887.

Application filed April 10, 1886. Serial No. 198,448. (No model.)

To all whom it may concern:

Be it known that we, RANSFORD WILCOX and SAMUEL L. PHILLIPS, of Milwaukee, in the county of Milwaukee, and in the State of Wisconsin, have invented certain new and useful Improvements in Machines for Reducing Wheat and Analogous Grain; and we do hereby declare that the following is a full, clear, and exact description thereof.

Our invention relates to machines for the reduction of wheat and analogous grain prior to grinding, and has for its objects to thoroughly disintegrate the kernels in a rapid manner and without making flour during such operation, thereby not only effecting a saving in time and material, but also aiding to secure a purer grade of the ground product than has heretofore been accomplished, as will be hereinafter described with reference to the accompanying drawings, making part of this specification, in which—

Figure 1 represents an elevation of our invention; Fig. 2, a diagram in cross-section of the disk-faces; Fig. 3, a plan view of the lower disk-face; Fig. 4, a similar view of the upper disk; Fig. 5, an enlarged detail plan view of the feed-regulator; Figs. 6, 7, and 8, diagram-sections, respectively, taken on lines *v v*, *w w*, and *x x*, Fig. 3; Fig. 9 represents a vertical transverse section of our machine; Fig. 10, a detail view of the key mechanism for fastening the disks to their spindles; Fig. 11, a horizontal cross-section on line *y y*, Figs. 1 and 9; Fig. 12, a detail view of a worm-gear for securing the vertical adjustment of the bottom disk; Fig. 13, a plan view of the bottom pulley that is keyed on the spindle of the upper disk; Fig. 14, a similar view showing the relative arrangement of the adjusting-blocks in the eye of the lower disk, and adjacent to the spindle of the upper disk and Fig. 15, an enlarged perspective view of the feed-regulator.

Referring by letter to the drawings, A represents the standards, and B B' the bridge-pieces that form the supporting-frame of our machine. Bolted or otherwise suitably secured to the upper flanged ends of the standards A is a horizontal table, C, that has a central depending hub, C'. Detachably connected to the table C is a sectional casing, D, and to the top of this casing is bolted the horizontal flange *a* of a hopper, E.

The casing D incloses two parallel disks, F

G, that are respectively keyed to the vertical spindles H I. The spindle I for the lower disk, 55 G, is entirely hollow, while the spindle H of the upper disk is solid throughout the greater portion of its length and partially inclosed by the hollow spindle I. The disk-spindles have preferably keyed thereto horizontal pulleys K 60 L, and these are differentially rotated in the same direction by belt-connection with other pulleys on a driving-shaft, (not shown,) thus imparting a similar rotation to the disks, the upper one, F, of the latter being driven at a 65 much higher rate of speed than the lower one, G, and both of said disks having their movement from right to left.

The disks F G are preferably provided with detachable chill-cast faces M N, that are secured in position by any suitable means, those shown consisting of annular ribs *b*, that fit corresponding grooves, *c*, in the main portions of the disks, and countersunk screws *d*, that serve to bind the parts firmly together. The disk-faces, being removable, are readily replaced should they become worn or fractured. The upper-disk face has its bosom *e* hollowed out to allow for the feed of the grain from the hopper E, that is bolted to the casing D and provided with a downward extension, *f*, designed to fit within the bored-out enlarged upper portion, *g*, of the spindle H, said enlarged portion of this spindle having passages *h*, through which the grain finds its way to the bosom *e* of the lower-disk face.

To prevent the grain from clogging in its descent from the hopper and at the same time insure an equal distribution through the spindle-passages *h*, we employ a casting consisting 90 of a hollow central stem, *k*, and wings *m*, the upper ends, *m'*, of the latter being turned down at right angles to a vertical, and the lower ends, *m''*, slightly flared out from such a line, this construction being illustrated in detail, 95 Fig. 5. This casting we insert within the bored-out portion *g* of the spindle H, the right-angular portions *m'* of the wings being interposed between the casing D and hopper-flange *a*, two of the bolts that serve to unite these 100 latter parts acting to secure said casting in a stationary position. The casting being stationary while the spindle revolves, the descending grain is kept agitated and directed toward the passages in said spindle.

The skirts of the disk-faces M N are formed

of a series of tangential furrows, n n' , that are narrow and concave at the peripheries of the respective bosoms e i , and gradually increase in width, while at the same time they decrease 5 in concavity until, as the circumferences of said faces are approached, each furrow assumes the form of an inclined plane, this construction being best illustrated by the diagram views, Figs. 6, 7, and 8. The furrows of each 10 disk-face are intended to be thoroughly smooth and highly polished. The greater degree to which this smoothness and polish is attained the better the result desired to be accomplished by our machine.

15 The above-described construction of the furrows in the disk-faces facilitates the feed of the grain from the bosoms toward the outer circumferences of the skirts, and prevents the kernels from being split prior to reaching the 20 inclined planes, the latter being most clearly shown by Fig. 8. The disks being rotated in the same direction at differential speeds, the grain by centrifugal force travels in the furrows of the faces M N toward the circumferences, and is rolled from one to the other on 25 the smooth and polished surfaces, thereby preventing the making of flour, there being no perceptible attrition. As the grain approaches the circumferences of the furrowed faces the 30 kernels are severally caught between the opposing inclined planes at the outer termini of the furrows and continue to be rolled along, as before described. The upper disk, F , being rotated at a greater speed than the lower 35 one, G , the lowest points of the inclined planes on the disk-face M at the outer termini of its furrows n will successively approach and pass the highest points of the similarly-located planes on the disk-face N , thereby gradually 40 contracting the intermediate spaces between these opposing inclined planes. This approach of the opposing inclined faces toward each other acts to exert a gradual pressure on the grain-kernels, and thus cause them to split apart at their seams without being crushed, 45 the comparative slow rotation of the lower disk, G , serving to cushion the stroke or pressure of the upper one, F , and thereby assist in accomplishing the desired result. The split 50 kernels fall upon the table C , between the rotating disks F G and casing D , and are finally discharged through a spout, O , into a suitable receptacle.

Upon the outer or hollow spindle, I , and located between the upper bridge-piece, B , and depending hub C' of the table C , is an internally-beveled collar, P , that is designed to be secured in place by a circular key, P' , encircling the spindle and driven down between the 55 latter and the beveled interior face of said collar. Fitted in a central screw-threaded aperture, o , in the bridge-piece B is a correspondingly-formed hub, Q' , of a worm-wheel, Q , the latter being arranged to mesh with a 60 worm-shaft, R , that has its bearings in the standards A , and is provided with a hand- 65

wheel, R' . The collar P bears against the worm-wheel Q , and when the latter is operated upon by the worm-shaft R the outer or hollow spindle is raised or lowered to vertically adjust the lower disk, G , thereby increasing or diminishing the space between the latter and the upper disk, F , according to the size of grain to be reduced. 70

If found desirable, the grain, after having 75 been split, as above described, may be again passed through the machine and further disintegrated, the proper vertical adjustment of the lower disk being effected to accomplish such operation. The upper ends of both spindles H I have their interiors and exteriors beveled, and are rigidly secured to the respective disks F G by hollow conical keys S , the latter being driven downward and acting to expand these upper spindle ends in the eyes of their 80 relative disks, this construction being illustrated in detail, Fig. 10 showing the parts detached.

The eye of the disk G is downwardly extended and forms the bore of a depending hub, G' , said extension of this eye being somewhat reduced in diameter. The upper or keyed end of the hollow spindle I fits within the extension of the lower-disk eye, and terminates immediately below a shoulder, p , formed by 85 the enlarged upper portion of the solid spindle H . The depending hub G' of the lower disk, G , comes within the similar part, C' , of the table C , but is of less diameter than the latter. Located in the space between the depending 90 hubs C' G' are truing-blocks T for the spindle I , said blocks being supported by an inward-projecting flange, r , at the lower end of the table-hub. These truing-blocks T are acted upon by set-bolts s , which operate in screw-threaded apertures in the depending hub C' of the table C , and by relatively loosening and tightening said blocks the upper end of the outer spindle can be readily adjusted to run true. The lower end of this outer spindle is 95 trued by means of wedge-blocks U U' , located in the pulley K , the blocks U being provided with bolt-extensions t , that pass through suitable apertures in the bottom of said pulley to receive regulating-nuts t' . The upper or enlarged end of the inner spindle is trued by a series of blocks, V , located in the space between said spindle and the circumference of the lower-disk eye. These blocks are acted upon by screw-rods V' , that are operative in radial 100 seats bored in the lower disk, G , the periphery of the latter being recessed to receive the heads of these rods, and thereby prevent them from projecting out in the space between this disk and the casing D , and the latter part is 105 provided with an opening or openings, d' , for the introduction of a socket-wrench to operate said screw-rods. The lower end of the spindle H is trued in a manner similar to the upper end thereof, the means consisting of blocks 110 W , that fit recesses in a central bearing, B' , of the bridge-piece B' , and set-bolts W' , operative 115 120 125 130 135

in screw-threaded radial seats bored in said bearing. Below the bridge-piece B' the spindle H is fitted with a collar, H', that serves to prevent upward movement of said spindle when the machine is in operation.

5 The upper face of the worm-wheel Q is recessed, and has inserted therein a series of friction-cones that form the bearing for the collar P, keyed to the spindle I. The central bearing, B², of the bridge-piece B' is also recessed and provided with a series of cones, on which latter the depending hub K' of the pulley K travels, this arrangement of parts also acting as a stop to prevent downward movement of 10 the spindle H. The collar H' is similarly constructed to receive a series of friction-cones that are interposed against the lower face of the bridge-piece B'.

Extending from an oil-cup, X, located above 20 the hopper E is a distributing-tube, u, that extends down through the center of said hopper and the stem k of the feed-regulator to enter a port, y, in the spindle H. From this port the oil finds its way down the full length of 25 the solid spindle, lubricating in its passage the several bearings for said spindle and the friction-cones located in the parts B² and collar H', the drip being caught by a shell, B³, bolted to the under face of the bridge-piece B'.

30 An oil-cup, Y, is located outside the machine, adjacent to the table C. A distributing-tube, z, leads from said cup through the depending table-hub C and terminates against the lower-disk hub G'. The lubricant from the cup Y 35 passes down the disk-hub G' and drips into the upper recessed portion of the collar P. From this point it finds its way down through ports b' in said collar to lubricate the friction-cones in the worm-wheel Q and the bearing-surfaces of the hub Q' and outer spindle, I. The lubricant now passes down the periphery of the spindle I and finds its way into the upper hollow portion of the pulley L, this latter being usually filled with waste to absorb said 45 lubricant. The excess of the lubricant not retained by the waste passes through ports c' in the pulley L, descends upon the wedge-blocks U U', and finally escapes down the spindle H to the shell B³.

50 Having thus fully described our invention, what we claim as new, and desire to secure by Letters Patent, is—

1. In a machine for reducing wheat and analogous grain, the combination of two opposing disks having their faces provided with a series of tangential furrows that are narrow and concave at their inner extremities and gradually increase in width and decrease in concavity toward their outer termini, where 55 they assume the form of inclined planes, substantially as set forth.

2. In a machine for reducing wheat and analogous grain, two parallel disks having their opposing faces provided with a suitable 60 dress, the spindle of the upper disk being solid and having a bored-out upper end pro-

vided with delivery-passages for the grain, and the spindle of the lower disk made hollow to surround the solid one, in combination with suitable pulleys keyed to the respective spindles to be differentially rotated in the same direction, as and for the purpose set forth.

3. In a machine for reducing wheat and analogous grain, two parallel disks the opposing faces of which have a suitable dress, the 75 spindle of the upper disk being solid and having a bored-out upper end that is beveled upon its interior and exterior, and provided with delivery-passages for the grain, and the spindle of the lower disk made hollow to surround 80 the solid one, and also interiorly and exteriorly beveled at its upper end, in combination with conical keys driven down inside the upper ends of the spindles, and means for imparting a differential rotation to said spindles in the same direction, as and for the purpose set forth.

4. In a machine for reducing wheat and analogous grain, two parallel disks the opposing faces of which have a suitable dress, a solid 90 spindle for the upper disk, that is bored out at its upper end and provided with delivery-passages for the grain, and a hollow spindle that surrounds the solid one and is keyed to the lower disk, and a suitable supporting-frame, in combination with a truing mechanism for the latter spindle, that comprises a series of suitable blocks located between said spindle and the circumference of the lower-disk eye, corresponding radial screw-rods 100 extended through the latter disk and arranged to bear on said blocks, similar blocks fitting recesses in the lower bridge-piece of the supporting-frame, and radial set-bolts operative in said bridge-piece, and means for differentially rotating said spindles in the same direction, as and for the purpose set forth.

5. In a machine for reducing wheat and analogous grain, a supporting-frame, two parallel disks the opposing faces of which are 110 provided with a suitable dress, a solid spindle for the upper disk, that is bored out at its upper end and provided with delivery-passages for the grain, a hollow spindle for the lower disk that surrounds the solid one, in combination with a truing mechanism for the former spindle, that comprises a series of suitable blocks located in a space between a depending hub of this spindle and a similar adjacent hub on the frame, a corresponding series of set-bolts operative in apertures in the latter hub, and wedge-blocks located in a pulley on said spindle, and means for differentially rotating the spindles in the same direction, as and for the purpose set forth.

6. In a machine for reducing wheat and analogous grain, a suitable supporting-frame and two parallel disks the opposing faces of which are provided with a suitable dress, a solid spindle for the upper disk, that is bored out at its 120 upper end and provided with delivery-passages for the grain, a hollow spindle for the lower

disk that surrounds the solid one, and a collar keyed to the latter spindle, in combination with a worm-wheel provided with a depending screw-threaded hub operative in the upper bridge-piece of the frame and arranged to bear against said collar, a transverse worm-shaft having its bearings in the frame-standards and arranged to mesh with said worm-wheel, and means for differentially rotating the spindles in the same direction, as and for the purpose set forth.

7. In a machine for reducing wheat and analogous grain, two parallel disks the opposing faces of which are provided with a suitable dress, a solid spindle for the upper disk, that is bored out at its upper end and provided with delivery-passages for the grain, and a hollow spindle for the lower disk that surrounds the solid one, in combination with a feed-regulator arranged to extend down into the bored-out extremity of said upper-disk spindle, and consisting of a central hollow stem provided with wings that have their upper ends turned down at right angles to a vertical, and their lower ends flared out from such a line, and means for differentially rotating said spindles in the same direction, as and for the purpose set forth.

8. In a machine for reducing wheat and analogous grain, two parallel disks the opposing faces of which are provided with a suitable dress, the upper disk-spindle being provided with a hollow upper extremity that has

delivery-passages for the grain, and an oil-port leading to the exterior of said spindle, and the lower disk having a hollow spindle that surrounds the solid one, in combination with means for differentially rotating said spindles in the same direction, and an oil-cup provided with a tube leading therefrom to the port in 40 said solid spindle, as and for the purpose set forth.

9. In a machine for reducing wheat and analogous grain, a horizontal table secured to a supporting-frame and having a depending hub, 45 two parallel disks having their opposing faces provided with a suitable dress, the spindles of said disks being arranged one within the other, and the lower spindle provided with a depending hub arranged within the one depending from said table, in combination with means for differentially rotating the spindles in the same direction, and an oil-cup located adjacent to said table and provided with a distributing-tube leading therefrom to the hub of 50 said spindle, as and for the purpose set forth.

In testimony that we claim the foregoing we have hereunto set our hands, at Milwaukee, in the county of Milwaukee and State of Wisconsin, in the presence of two witnesses.

RANSFORD WILCOX.
